UNITED STATES PATENT OFFICE.

WALTER EGGINTON, OF CORNING, NEW YORK.

DESIGN FOR THE ORNAMENTATION OF GLASS OR OTHER VESSELS.

SPECIFICATION forming part of Design No. 22,136, dated January 17, 1893.

Application filed December 21, 1892. Serial No. 451,945. Term of patent 14 years.

To all whom it may concern:

Be it known that I, WALTER EGGINTON, a citizen of the United States, and a resident of Corning, in the county of Steuben and State of New York, have invented and produced a new and original Design for the Ornamentation of Glass or other Vessels, of which the following is a specification, reference being had to the accompanying drawing, forming part thereof, and which represents a bottom view of a glass tray ornamented with my design.

The leading features of my design consists of the large central figure having radial lines representing extending and withdrawing rays, the pelecoid figures, and the double-pointed figures between the pelecoid figures; thus forming what I call the "Valencian" design.

1 is a central figure having radial lines imparting thereto the appearance of extending and withdrawing rays. These lines separate

pelecoid figures 2 each having a central large rosette 3 on the outer portion surrounded by angular figures 4, and a small central rosette 5 on the inner portion surrounded by angular figures 6.

7 are double-pointed figures located between the pelecoid figures, each having a rosette 8 on the outer portion surrounded by angular figures 9 and lattice work figures 10 on the inner portion.

Having thus described my invention, the following is what I claim as new therein and desire to secure by design Letters Patent:

The design for the ornamentation of glass or other vessels, substantially as herein shown 35 and described.

WALTER EGGINTON.
